DRAPERY PLEATER GAUGE

Orlando A. Chadwick, Denver, Colo., assignor to
Chadco, Inc., Denver, Colo.

Filed Feb. 19, 1975, Ser. No. 551,166

Term of patent 14 years

Int. Cl. D10—04

U.S. Cl. D10—62

Fig. 1

Fig. 2

Fig. 3

Fig. 4

Fig. 5

FIG. 1 is a left front perspective view of a drapery pleater gauge showing my new design;

FIG. 2 is a top plan view thereof, the bottom being plain and unornamented;

FIG. 3 is a front elevational view thereof;

FIG. 4 is a right end elevational view thereof;

FIG. 5 is a perspective view of the slider with the holder omitted for ease of illustration, both sliders being identical.

I claim:

The ornamental design for a drapery pleater gauge, as shown and described.
